UNITED STATES PATENT OFFICE.

CHARLES H. OSLUND AND JOHN EMANUEL JOHNSON, OF WORCESTER, MASSACHUSETTS, ASSIGNORS TO THE O & J MACHINE COMPANY, OF WORCESTER, MASSACHUSETTS, A CORPORATION OF MASSACHUSETTS.

CROWNING MACHINE.

Application filed December 27, 1923. Serial No. 683,075.

This invention relates to a machine for sealing metal caps or crowns on bottles, the machine being most commonly used in sealing bottles containing ginger ale, soda, or 5 other similar soft drinks. Much difficulty has been encountered in the operation of such machines on account of the variations in height of the different bottles, as these variations in height have resulted in variations in 10 sealing pressure which have caused the breakage of many bottles.

It is the principal object of our invention to provide a crowning machine in which the machine automatically adapts itself to the 15 varying heights of the bottles to be sealed and in which a uniform sealing pressure is provided throughout the whole height range of the machine's capacity.

A further object of our invention is to provide a single, improved, and much simplified device for simultaneously adjusting the sealing pressure of all of the different crowning plungers in the machine. We have also provided improved driving connections to rotate the plunger carrier and bottle support simultaneously.

With these general objects in view, particular features of our invention consist in certain arrangements and combinations of parts 30 disclosed in the drawings and hereinafter described, and more specifically set forth in the appended claims.

A preferred form of the invention is shown in the drawings in which—

Fig. 1 is a sectional elevation of our improved machine with the bottle feeding devices omitted;

Fig. 2 is a sectional plan view, taken along the line 2—2 in Fig. 1 and showing also the bottle feeding devices;

Fig. 3 is a sectional elevation of one of the sealing or crowning plungers, together with operating and adjusting mechanism therefor;

Fig. 4 is a detail sectional plan view, taken along the line 4—4 in Fig. 3;

Fig. 5 is an enlarged detail sectional elevation of the lower end of one of the sealing plungers; and

Fig. 6 is a detail elevation, looking in the direction of the arrow 6 in Fig. 3.

Referring to the drawings, we have shown a crowning machine comprising a base 10, a table casing 11, a column or support 12, and an upper head or bearing frame 13, all of

these parts being rigidly secured together to form a complete frame. One or more rods 14 support the front end of the bearing frame 13 and have their lower ends fixed in the table casing 11.

A bottle support or disc 15 is rotatably mounted near the center of the table casing 11 and is secured to an upright shaft 16 having upper and lower bearings in the frame of the machine. A gear 17 is fixed to the under side of the bottle support or disc 15 and is driven by a pinion 18 on a vertical shaft 19 rotatably mounted in the frame of the machine and having a bevelled gear 20 at its upper end engaged by a pinion 21 on the horizontal shaft 22 supported in bearings on the head frame 13. The shaft 22 may be connected by a clutch 23 with a suitable driving mechanism such as a motor 24 and a hand wheel 25 may be provided for turning the 70 machine manually for purposes of adjusting or setting. A handle 26 at the front of the machine is connected for manual actuation of the clutch 23.

A cross head 30 is slidably mounted on the rod 14 and shaft 16 and may be vertically adjusted by a pair of threaded shafts 31 having bearings in the head 13 and provided with bevelled gears 32 meshing with pinions 33 on a shaft 34 which may be manually rotated by a handle 35.

A depending member 36 is bolted to the under side of the cross head 30 and is provided with a helical flange or cam 37 for a purpose to be described. A plunger carrier 38 is centered on the shaft 16 below the depending member 36 and is supported by a ring 39 secured to the carrier 38 and engaging the upper face of an annular flange 40 on the lower end of the member 36. The ring 39 has a vertically slotted outer cylindrical wall 39a.

The carrier 38 is provided with gear teeth 41 about its periphery, meshing with an elongated pinion 42 fixed on the vertical drive shaft 19. Gear 41 and pinion 42 correspond in ratio to the gear 17 and pinion 18 previously described, so that the bottle support 15 and plunger carrier 38 are simultaneously rotated at the same speed but neither of these members is driven by the centering shaft 16.

A plurality of sealing plungers 44 are mounted for vertical sliding movement in the plunger carrier 38. Each plunger 44 comprises a casing 45 (Figs. 3 and 5) with

in which is slidably mounted a sealing member 46. A bottle guide and crown or cap holder 47 is threaded into the lower end of the sealing member 46 and may be held from 5 relative rotation therein by a flat spring 48 (Fig. 5) seated in longitudinally disposed slots in the lower end of the member 46 and in the outer cylindrical surface of the guide 47. A pin 50 in the member 46 limits upward movement of the spring 48 and a stud 51 in the spring seated in a corresponding opening in the guide 47 prevents downward displacement of the spring. Thus the spring forms in effect a convenient detachable key 10 for the bottle guide and crown holder 47.

A spring 52 (Fig. 3) yieldingly depresses each member 46 and provides yielding sealing pressure for the crowns C. A nut 53 is threaded on the upper end of each sealing member 46 and provides means for adjusting the sealing member vertically relative to the casing 45. A sealing die 54 of the usual type is secured in the lower end of the sealing member 46 and an ejecting member 55 is slidably mounted in the member 46 and is yieldingly held downward by a spring 56. An ejecting rod 57 contacts with the upper end of the ejecting member 55 and projects beyond the upper end of the plunger where it 20 may be struck a substantial blow manually or otherwise to eject a crown which may become lodged in the lower end of the plunger.

Each plunger 44 is provided with a cam roll 60 fixed to one side of the plunger and projecting through a slot in the cylindrical wall 39^a in position for engagement with the helical flange or cam 37 on the cross head member 36. Each sealing plunger 44 is also provided at its upper end with a cam surface 61 (Fig. 6) positioned to pass under a cam roll 62 rotatably mounted on the lower end of a slide 63. The slide 63 is mounted for vertical movement in a bearing 64 on the cross head 30 and is provided with transversely extending notches or teeth 65 (Fig. 3).

A pair of pawls 66 and 67 are mounted on a stud or cross pin 68 fixed in the bearing 64, and springs 69 yieldingly move the pawls 66 and 67 to engage the notches 65. It will be noted that the pawl 67 is slightly longer than the pawl 66, by an amount substantially equal to one half of a notch or tooth 65.

A lever 70 is pivoted on a rod or shaft 71 (Fig. 4) which extends through two side members 72 of the cross head 30 and which is threaded into one of the side members. A lock nut 73 is provided by which it may be secured in transversely adjusted position. Collars 75 at each side of the lever 70 prevent axial movement of the lever relative to the shaft 74, which may be squared at 76 to receive a wrench for adjustment as will be hereinafter described.

An annular cam plate 77 (Fig. 4) is mounted to rotate with the plunger carrier 38 and

is provided with a plurality of cam surfaces 78 corresponding in number to the number of sealing plungers 45. The lever 70 is provided with a cam roll 79 at its lower end engaging the cam plate 77. The lever 70 is 70 normally pressed against the upper ends of the pawls 66 and 67 by a spring 70^a (Fig. 3) and thus holds the pawls inoperative until the lever is engaged by one of the cams 78.

A star wheel 80 (Fig. 2) may be mounted 75 to rotate with the bottle support 15 and any usual means may be provided for feeding bottles to the support and removing bottles therefrom. We have shown a gate or support 81 which is periodically withdrawn to 80 permit a bottle B to be advanced by a disc 82 to the bottle support 15 and star wheel 80. A wiper 83 accurately positions the bottles in the star wheel and an ejecting guide 84 removes the bottles after the sealing operation. 85 The gate 81 is preferably pivoted on a guide casting 85 and is held closed by a lever 86 mounted on shaft 19. Lever 86 is provided with roll 87 positioned for engagement by the points of the star wheel 80 as 90 it is continuously rotated. Further description of the bottle feeding and removing mechanism is unnecessary as it constitutes no essential part of our present invention.

Having thus described the construction of 95 our improved machine, the method of operation is as follows: The cross head 30 is first adjusted vertically to a position such that the plungers 44 when in raised position will have ample clearance above the longest bottle to be sealed. As the plunger carrier and bottle support are rotated, the cam roll 60 of each plunger gradually descends the helical cam 37, allowing the plunger to rest freely upon the top of its associated bottle. As 100 these bottles vary in height, the plungers approaching sealing position will also vary in vertical position and the cams 61 will be at corresponding different elevations.

The roll 62 is engaged by each cam 61 as 110 each plunger and associated bottle approach sealing position and each cam 61 raises the roll 62 and slide 63 as it passes under the roll 62 until the roll 79 on the lever 70 is engaged by the corresponding cam 78 115 (Fig. 4) on the cam ring 77. The lever 70 is then swung anti-clockwise to the position shown in Fig. 3, releasing the pawls 66 and 67 to engage and lock the side 63 in the position to which it has at that instant 120 been raised by the associated cam 61.

The cam roll 62 being thereafter fixed in vertical position, the sealing plunger 44 will be depressed a uniform distance equivalent to the remaining elevation of the cam 61, thus sealing the bottle with a uniform pressure. If it is desired to increase or decrease this uniform pressure for all of the sealing plungers, this may be readily accomplished by adjusting the lever 70 laterally, loosening the 130

nut 73 (Fig. 4) and turning the rod 71 in its threaded bearing. This will cause each cam 78 to engage the lever 70 either earlier or later in its travel as is desired, thus locking the slide 63 at a different point relative to the elevation of the cam 61.

Accordingly it will be seen that we have provided a crowning machine in which each sealing plunger is automatically adjusted to each bottle presented to it, as it approaches sealing position, and that a uniform depression of the sealing head is provided after such adjustment of each plunger. In actual practice, it is found that this mechanism will adapt itself to bottles varying in height by more than one inch and that both long and short bottles are uniformly sealed.

Having thus described our invention and the advantages thereof, we do not wish to be limited to the details herein disclosed otherwise than as set forth in the claims, but what we claim is:—

1. A crowning machine having in combination, a support for a plurality of bottles, a plurality of sealing plungers each movable to sealing position with an associated bottle, a single device coacting with all of said plungers for depressing each of said plungers successively, means to secure said single device in different vertical positions, each selectively corresponding to the height of the bottle about to be sealed, and additional mechanism effective by a single adjustment to vary the extent of the depressing movement of every one of said plungers resultant from engagement with said single device.

2. A crowning machine having, in combination, a support for a plurality of bottles, a support for sealing mechanism, a plurality of sealing plungers each movable vertically in said support to sealing position with an associated bottle, means to selectively apply uniform sealing pressure to all of said bottles, and additional mechanism effective by a single adjustment to increase or decrease said uniform sealing pressure with respect to all of said bottles while the sealing mechanism support remains at a fixed elevation.

3. In a crowning machine, a bottle support, a plurality of sealing plungers, a rotary carrier for said plungers, a single drive shaft and separate driving connections from said drive shaft to said bottle support and to said plunger carrier, said connections being effective to rotate said support and said carrier simultaneously and at the same speed when said drive shaft is rotated.

4. In a crowning machine, a bottle support, a shaft to which said support is secured, a plurality of sealing plungers, a carrier for said plungers centered and loosely rotatable on said shaft, a drive shaft and separate driving connections from said drive shaft to said support and to said plunger carrier, said connections being effective to rotate said

support and carrier simultaneously and at the same speed.

5. In a crowning machine, a bottle support, a shaft to which said support is secured, a plurality of sealing plungers, a carrier for said plungers centered and loosely rotatable on said shaft, a vertical driving shaft, a gear on said bottle support, a pinion on said driving shaft engaging therewith, a gear on said plunger carrier, means to adjust said carrier vertically, and an elongated pinion on said driving shaft engaging said latter gear in every vertical position thereof.

6. A crowning machine having in combination a support for a plurality of bottles, a plurality of sealing plungers each movable to sealing position with an associated bottle, a device coacting with the plungers for depressing same, a toothed bar on which said device is mounted, a pawl mounted on a fixed pivot and positioned to engage said bar, means to hold said pawl out of engagement with said bar, and a cam ring rotatable with the bottle supports and coacting with said means to render said pawl operative as each bottle support reaches a predetermined angular position.

7. A crowning machine having in combination a support for a plurality of bottles, a plurality of sealing plungers each movable to sealing position with an associated bottle, a device coacting with the plungers for depressing same, a vertically sliding bar on which said device is mounted, means to hold said bar from upward movement, devices to maintain said holding means out of engagement with said bar, and means to release said holding means as each bottle support reaches a predetermined position.

8. A crowning machine having in combination a support for a plurality of bottles, a plurality of sealing plungers each movable to sealing position with an associated bottle, a device coacting with the plungers for depressing same, means to relatively adjust each plunger and said device vertically above an associated bottle as it approaches sealing position, and means to lock said device in adjusted position relative to said plunger, said locking means including a lever, a series of cams rotatable in spaced relation with said bottle support, and means to adjust said lever tangentially relative to the path of rotation of said cams to thereby vary the position of contact therewith.

9. A crowning machine having in combination a support for a plurality of bottles, a plurality of sealing plungers each movable to sealing position with an associated bottle, a device coacting with the plungers for depressing same, means to relatively adjust each plunger and said device vertically above an associated bottle as it approaches sealing position, and means to lock said device in adjusted position relative to said plunger, said

locking means including a lever, a series of cams rotatable in spaced relation with said bottle support, and means to vary the position of contact of said lever and cams by 5 relative adjustment of one of said members.

10. A crowning machine having in combination a support for a plurality of bottles, a plurality of sealing plungers each movable to sealing position with an associated bottle, 10 a device coating with the plungers for depressing same, a toothed bar on which said device is mounted, a pair of pawls engaging said bar in half-tooth relation, means including a spring effective to hold said pawls out 15 of engagement with said bar, and means to overcome said spring and permit said pawls to engage said bar in fixed relation to the movement of the bottle supports.

11. A crowning machine having in com-

bination a support for a plurality of bottles, 20 a plurality of sealing plungers each movable to sealing position with an associated bottle, a device coating with the plungers for depressing same, means to relatively adjust each plunger and said device vertically above 25 an associated bottle as it approaches sealing position, and means to lock said device in adjusted position relative to said plunger, said locking means including a lever, a series of cams rotatable in spaced relation with said 30 bottle support, and means to move the bearing of said lever axially to vary its position of contact with said cams.

In testimony whereof we have hereunto affixed our signatures.

CHARLES H. OSLUND.
JOHN EMANUEL JOHNSON.
